UNITED STATES PATENT OFFICE.

CHARLES S. RUEF, OF DIXON, ILLINOIS, ASSIGNOR TO THE GRAND DETOUR PLOW COMPANY, OF SAME PLACE.

CULTIVATOR.

SPECIFICATION forming part of Letters Patent No. 444,186, dated January 6, 1891.

Application filed August 28, 1890. Serial No. 363,363. (No model.)

To all whom it may concern:

Be it known that I, CHARLES S. RUEF, a citizen of the United States, residing at Dixon, in the county of Lee and State of Illinois, 5 have invented certain new and useful Improvements in Cultivators; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 My invention relates to improvements in cultivators in which the shovels are carried upon depending arms, and is especially applicable to corn-cultivators wherein variant positions of the shovels are required at different periods of the growth of the corn.

The objects of my invention are, first, to provide ready means for adjusting the inclination of the respective shovels laterally; second, other means for securing said adjustment longitudinally or in the direction of the movement of the machine; third, other means for effecting the vertical adjustment of the shovel bodily. I attain these objects by the mechanism illustrated in the accompanying drawings, in which—

Figure 1 is a side elevation of the lower end of the usual curved beam and the attachment of the shovel thereto, the changes of altitude of the shovel and its position when the break-pin is casually broken being shown in dotted lines. Fig. 2 is the same, showing in dotted lines the extreme adjustment of the shovels longitudinally or in the line of the movement of the machine. Fig. 3 is a cross-section in the line $\alpha\alpha$ of Fig. 1, exhibiting the mechanism employed for adjusting the shovel laterally. Fig. 4 is a rear elevation of the lower end of the beam, the shovel-arm, and shovel. Fig. 5 is a detail of the clamping-washers seated at the junction of the beam and shovel-arm. Fig. 6 is a plan view of the elliptical corrugated clamp formed on each side of the upper end of the shovel-arm.

As my invention pertains only to modes of attaching the shovel to the plow-beam to obtain the variant adjustments mentioned, and

is applicable to any of the well-known types of cultivators, I do not deem it necessary to show or describe the entire machine or further than will render intelligible the construction, location, and operation of my invention; and, further, inasmuch as my invention is similarly applied to each of the shovels employed, I will limit the illustration and description to one shovel and its beam-connection.

A is the usual plow-beam, attached in any suitable mode at its forward end to the carrying or draft mechanism, and provided with the transverse opening 1 as the pivot-seat of its shovel-arm and the lower or transverse opening 2 for the usual wooden break-pin employed to exercise only a limited degree of resistance and permit the shovel to swing back in case of contact or engagement with immovable obstacles.

B is a shovel-arm, bifurcated at its upper end to pass up on each side of the lower end of the beam A. On the upper end of the arm B there is provided on each side of the beam A an elliptical clamp C, provided on its exterior side with vertical corrugations 6. The clamps C are placed longitudinally of the machine, and are provided with the central segmental longitudinal slot 7 to receive the transverse bolt 5, which attaches the arm B to the beam A. Between the head and nut of the bolt 5, respectively, and the corrugated surface of the clamp C are interposed circular washers D, provided on their interior faces with vertical corrugations 8, adapted to engage the corrugations 6 of clamp C, as shown in Fig. 5. The longitudinal adjustment of the shovel E is effected by releasing the bolt 5, and thereby the washers D, from engagement with the clamp C and moving the shovel-arm B forward or back into the desired position and then tightening said washers into the clamp C by means of the nut on bolt 5.

F is the usual break-pin, seated transversely through the central opening 10 in the shovel-arm B and the lower opening 2 in the beam A. In the casual breaking of the pin F the shovel E and arm B are permitted to swing backward in the position shown in dotted lines in Fig. 1. In such backward swing of

the shovel and arm the clamp C and washer D rotate upon the pin 5, and when said arm is again brought into position so that its opening 10 will register with the opening 2 5 the arm will be in the same position it occupied previous to said breakage.

The lower end of the shovel-arm B is provided peripherally with vertical corrugations 11 on each side thereof. The shovel-shoe G 10 is suitably formed at its front end to receive the shovel E, and is provided at its rear end with the rearward, extending bifurcations 12 and 15, which pass, respectively, on each side of the lower end of the arm B. That portion 15 of the bifurcations 12 and 15 in contact with the arm B has an inner concavity 13, adapted to conform to the periphery of the arm B, and in said concavity are formed corrugations 14 conformable to the external corrugations 11 of 20 said arm. In the rear end of the shoe G there is seated a transverse bolt H, by the loosening and tightening of which said shoe can be released from or clamped upon the arm B. In the lateral adjustment of the shovel E the 25 bolt H is released sufficient to permit the bifurcations 12 and 15 to be sprung outwardly and disengage the corrugations 11 and 14, when the shovel can be turned laterally to the desired position and said corrugations 30 permitted to re-engage and the bolt H tightened. The vertical adjustment of the shoe G and shovel E bodily is effected in substantially the mode last described and by the same means—that is to say, the bolt H is loosened 35 and the shoe G, carrying the shovel E, is moved upward or downward on the adjacent end of the shovel-arm B into any desired alti-

tude and rigidly affixed there by the tightening of said bolt H. The corrugations 11 and 14 need be only slight, and the elasticity in 40 the bifurcations of the shoe G are sufficient to release their mutual engagement when the bolt H is loosened.

It will be observed that the mechanism hereinbefore described affords the aforesaid means 45 of adjusting the shovel E in three different directions—that is to say, vertically, laterally, and longitudinally. The means of adjustment are simple, strong, and durable, and each and all of them easy of access.

What I claim as my invention, and desire to secure by Letters Patent of the United States, is—

In a cultivator attachment, the combination, with the shovel-bearing arm B, the upper end 55 of which is bifurcated and provided with the slotted corrugated clamps and the break-pin holes and the lower end is round and provided with vertical corrugations, of a shovel-shoe G, suitably formed at its front end to receive the shovel and provided at its rear end with the rearwardly-extending elastic bifurcations, and having an inner cavity provided with vertical corrugations to conform with and fit upon the round corrugated portion of 60 the arm B, and a transverse bolt H through the bifurcations, substantially as described.

In testimony whereof I affix my signature in presence of two witnesses.

CHARLES S. RUEF.
